(57) **CLAIM**

The ornamental design for an electrical plug connector, as shown and described.

DESCRIPTION

FIG. 1 is a top plan view of the first embodiment of an electrical plug connector showing our new design, the bottom plan view being identical thereto;

FIG. 2 is a front elevation view thereof, the rear plan view being identical thereto;

FIG. 3 is a right side elevation view thereof;

FIG. 4 is a left side elevation view thereof

FIG. 5 is a top plan view of the second embodiment of an electrical plug connector showing our new design, the bottom plan view being identical thereto;

FIG. 6 is a front elevation view thereof, the rear plan view being identical thereto;

FIG. 7 is a right side elevation view thereof; and,

FIG. 8 is a left side elevation view thereof.
